No. 834,371.

PATENTED OCT. 30, 1906.

H. A. DUC, JR.
ELASTIC FLUID ENGINE.
APPLICATION FILED NOV. 23, 1905.

James P. Mansfield. BY Alexander V. Towell, Attorney.

UNITED STATES PATENT OFFICE.

HENRY A. DUC, JR., OF CHARLESTON, SOUTH CAROLINA.

ELASTIC-FLUID ENGINE.

No. 834,371.

Specification of Letters Patent.

Patented Oct. 30, 1906.

Application filed November 23, 1905. Serial No. 288,750.

To all whom it may concern:
Be it known that I, HENRY A. DUC, Jr., of Charleston, in the county of Charleston and State of South Carolina, have invented certain new and useful Improvements in Elastic-Fluid Engines; and I hereby declare that the following is a full, clear, and exact description thereof, reference being had to the accompanying drawings, which form part 10 of this specification.

This invention is an elastic-fluid engine designed to operate at high speed with great efficiency and economy.

The major object of this invention is to 15 utilize the motion of the elastic fluid while passing through an expanding-tube into the revolving wheel of turbines to exhaust the wheel-chambers, so that the wheels will rotate in as high a vacuum as it is possible to 20 maintain by an induced current, and to continue the expansion of the fluid in the same direction and use its reaction while passing through the revolving wheels, and thereby avoid all back pressure or resistances, such 25 as occur in reversing the fluid.

Subsidiary objects of the invention are to eliminate skin friction or surface friction caused by contact of steam against the moving parts, to so construct the parts that the 30 main fluid flow will operate to induce partial vacuum in the wheel-chambers surrounding the exterior of the wheels, and also, if desired, to assist the condenser to produce a perfectly balanced engine, and to partially 35 float the rotative parts on the propelling fluid when used vertically, thus eliminating much of the weight upon the step-bearings, and thereby increase the efficiency of the engine.

Further objects are to obtain the full 40 reactive effect of the jets of fluid from the peripheries of the wheels or disks by allowing them to escape into an annular chamber or space leading to a condenser and also to provide means for utilizing the expansive force 45 of steam when the same is used as the propelling fluid.

The invention will be clearly understood from the following description, in connection 50 with the drawings forming part of this specification, and the features and combinations of parts for which protection is desired are set forth in the several clauses of the claim.

In the drawings, Figure 1 is a sectional

elevation of an engine embodying the invention and designed to utilize the expansive force of steam or like propulsive fluid. Fig. 2 is a sectional end elevation of Fig. 1 on line 22, Fig. 1. Fig. 3 is a detail view of one of the jet-wheels. Fig. 4 is a sectional detail view of a multiple jet-wheel. Fig. 5 is a sectional view of a modification, showing a twin balanced engine; and Fig. 6 is a detail of journal. 65

Referring more particularly to Fig. 1, A designates the casing of one of the power or jet wheels, having an annular chamber A', with preferably converging, but may be parallel, sides and rounded at internal and external edges, the opening or mouth of the chamber surrounding the periphery of the reaction-wheel B to admit the easy ingress of the elastic fluid when slight lateral movement takes place and facilitates its outward 75 flow. The reaction-wheel B is rotatably mounted upon an axially-disposed shaft C. The said reaction-wheel is provided with equidistant jet-passages, which extend from the axis to the periphery of the wheel, being 80 of much greater area at center than at their periphery and being curved, as shown, so as to obtain the greatest reactive effect from the escaping fluid. As shown in Fig. 3, there are but two such passages; but their 85 number may be increased, provided the balance of the wheel is not disturbed. The wheel is provided at center with a fluid-inlet b', preferably formed in an elongated hub or flange b'', which communicates at its outer 90 end with a short sleeve D, having a radial flange d, by which it is secured in position in the end of the casing A, as shown. Preferably the inner end of sleeve D is tapered exteriorly to fit in the corresponding internally- 95 tapered end of hub b'', forming a conical running-joint b'', opening in the direction of the flow of the fluid, so that the latter will tend to induce into the wheel any fluid which might leak into the casing exterior to the 100 joint.

The flaring sleeve D forms part of the steam-inlet or expanding tube and is held concentric with the running-joint b'' in any convenient manner. The sleeve D in turn 105 communicates with a fluid-supply. As shown at the right-hand side of Fig. 1, it communicates with a fluid-supply and injector-head E, having a main fluid-inlet e, an outlet e', and an injector-nozzle e'', which connects with a 110

pipe P, hereinafter referred to, so that the inflowing fluid will create a partial vacuum in pipe P for a purpose hereinafter described. The fluid passage-way from head E to the 5 wheel gradually enlarges, so as to allow the fluid to travel at the highest velocity without appreciable loss by friction and enters the jet-passages and streaming therethrough jets into the chamber A' and by its reaction causes 10 the wheel to rotate in a direction opposite to the jets at great speed.

It is well known to engineers that no energy can be absorbed without molecular displacement, and accordingly no power is required to 15 hold any amount of potential energy in position, and likewise no energy is absorbed from violent molecular movement to maintain a high tension on a space in vacua produced by the induction thereof after the space is emp- 20 tied and only a very limited amount utilized to withdraw any small leakage which may occur. It is also well known that all surfaces in rapid motion surrounded by any medium encounter considerable resistance, commonly 25 known as "fluid-brake," "water-brake," or such. Therefore it is very important to avoid all constructions which expose any high-speed mechanism to such influence, and to obviate this difficulty those versed in turbine-work 30 have endeavored as far as possible to provide means to prevent leakage into the wheel-chambers by means of rings, close-fitting running-joints, or baffle-rings, &c. I accomplish the desired end in the following novel 35 manner: The wheel is adapted to work as close as possible to the mouth of the chamber A', but there will necessarily be clearance-spaces left at the sides of the wheel, and to prevent accumulation of pressure therein 40 and consequent retarding skin friction I exhaust the leakage from the chambers a a at the sides of the wheel. I can accomplish this in one or more ways. As shown, these chambers a a are connected by branch pipes 45 p' with a header p, leading to pipe P, so that the suction in the latter caused by the action of the jet-head E will create a partial vacuum in the chambers a a and obviate much of the friction and retarding effect incident to as- 50 simulation of pressure in chambers a a.

I have shown a single jet at the steam entrance connected with the wheel-chamber, but it is possible to use two or more jets on the same inlet, so that one will aid the other 55 to secure a higher vacuum and connect the whole with a condenser of suitable construction. The chambers a a may also be exhausted, if desired, by means of apertures a', leading from chambers a into the chamber A' 60 adjacent the periphery of the reaction-wheel and in such position that the escaping jets of fluid from the reaction-wheel rushing across the mouths of the apertures produce a partial vacuum therein and act somewhat like 65 exhausts to empty the chambers a. Thus

practically the reaction-wheels are relieved of much extraneous skin friction and do not rotate enveloped by the active fluid. The jets issuing into chamber A' will tend to lessen the friction on the periphery of the wheel. 70 This invention can be easily applied to turbines having peripheral vanes and can be utilized on engines already in use with many advantages.

To show how the expansive force of the 75 fluid may be utilized, I have illustrated in Fig. 1 a second reaction-wheel, constructed and incased like the first, but of larger diameter and mounted on a prolongation of the shaft of the first wheel, similar parts differ- 80 ing only in size, being similarly lettered in the drawings. The discharged fluid is led from chamber A' of the first engine into a globular head E² (which in this case need not be a jet-head) by a connecting-pipe A³, the fluid-pas- 85 sages being gradually enlarged to compensate for the increased volume of fluid and to allow its continuous expansion and reduce the friction.

The shafts C are journaled in suitable bear- 90 ings, preferably collared so as to resist the end thrust of the fluid against the wheels, and may be lubricated in any preferred manner, the bearings and mode of lubricating them employed not forming part of present inven- 95 tion; but I have indicated in the drawings a constantly-lubricated bearing, the lubricant being supplied through pipe f and drained off through pipe f' into a receptacle F. The header p is provided with a valve p², by which 100 communication with pipe P may be closed when desired. It is also provided with a removable cap p³, so that it may be connected to any preferred form of exhaust or to a separator, if desired, (not shown,) and 105 the exhaust from the second or final low-pressure wheel may be connected so as to open to the atmosphere or lead to a condenser in the usual manner.

As shown in Fig. 4, the reaction-wheel is 110 provided with a series of parallel jet-apertures b⁴, all communicating with a common central chamber, so that fluid may be admitted at both sides of such wheel, so as to obviate any end thrust on its bearings. 115

As shown in Fig. 5, two equal-sized reaction-wheels are mounted in adjacent similar castings communicating with the adjacent reaction-wheel passages and also having a double ejector-nozzle e⁶, communicating by a 120 pipe P' with a header p, the parts being otherwise constructed substantially as described and indicated by the letters of reference thereon. In this engine the wheels are perfectly balanced and being opposed neutralize the end thrust on the shaft. 125

Operation: Steam or elastic fluid admitted into jet-head E will induce the matter in pipe P and exhaust the wheel-chambers a a and continuously remove any leakage that 130

occurs, so that the reaction-wheels can rotate with very little fluid-brake action while expanding outward into and rotating reaction-wheel B and flowing from the jets circumferentially over the apertures a' a' into the annular expanding-chamber A' , creating jet action to aid in removing leakage between running-joints, and after being whirled into the annular chamber A' it passes through expanding-pipe A^3 to the second reaction-wheel and imparts further rotative energy thereto and is finally discharged. Pipe P is provided with drip P, suitably closed or connected with any common regulating device, and a valve. Tank h is used to drain the lubricant in any of the well-known ways as it flows in from the tube h'.

The construction shown in Fig. 1 can operate with great advantage if arranged vertically with a jet or jet-heads at the bottom and provided with conical journals and a partly-balanced step-bearing, or the shaft and wheels combined, suspended from the end of a fulcrumed lever or counterbalanced by a spring or equivalent, having a detrusive resistance equal to the vertical load of the wheels and shaft minus the upward pressure of the inflowing elastic fluid, as the escaping fluid issuing at the periphery equally at opposite points, producing no unequal lateral application of energy, will cause the wheels and shaft combined to spin like a top and rotate about the true center of gravity of the revolving wheels and shaft combined, embraced in the issuing steam or elastic fluid, practically requiring no lateral support, and since the upward pressure of the inflowing steam or fluid plus the lifting power of the spring or its equivalent will lift the shaft and wheels to their working position and raise the conical journals of the shaft sufficiently to leave their absolute contact with the conical surfaces of their lateral supports, so that practically the wheels and shaft will run almost frictionlessly on the upward-flowing steam or elastic fluid, requiring little or no lubricant, the steam or elastic fluid being utilized in this arrangement, first, to remove fluid-brake action; secondly, to counterbalance much of the step-load, and, thirdly, for reducing the journal friction, and it can assist in operating the condenser when so desired.

Obviously the forms of the casings may be varied and constructed with chambers leading from the outer annular chamber A' to the central inlet b of the other, so as to dispense with pipe A^3 , and any number of reaction-wheel casings could be secured together within the scope of this invention, it being only a matter of convenience and cost.

Having thus described my invention, what I claim as new, and desire to secure by Letters Patent, is—

65 1. In a turbine-engine, a reaction-wheel,

and an inclosing expanding-chamber into which the fluid escapes from the wheel and a jet-head discharging axially into the wheel.

2. In a turbine-engine, the combination of an annular expanding-chamber having a continuously open mouth or inlet around its inner periphery; with a reaction-wheel fitted to rotate within the mouth of the annular chamber and having peripheral jet-openings, and a jet-head discharging elastic fluid axially into said reaction-wheel.

3. In a turbine-engine, a reaction-wheel, and an inclosing expanding-chamber into which the fluid escapes from the wheel, and means for removing pressure at the sides of the reaction-wheel.

4. In a turbine-engine, the combination of an annular expanding-chamber having an open mouth or inlet around its inner periphery; with a reaction-wheel fitted to rotate within the mouth of the annular chamber and having peripheral jet-openings, means for introducing elastic fluid axially into said reaction-wheel; and means for creating a partial vacuum in the casing around said wheel and outside the expanding-chamber, substantially as described.

5. In a turbine-engine, an expanding-chamber having an outlet, and an annular mouth, a reaction-wheel disposed axially of said chamber with its periphery closing the mouth thereof, said reaction-wheel having a central fluid-receiving chamber, and equidistant radiating jet-passages opening into the expanding-chamber at the periphery of the wheel, and a jet-head for introducing elastic fluid axially into the wheel, substantially as described.

6. In a turbine-engine, an expanding-chamber having an outlet and an annular mouth, and a reaction-wheel disposed axially of said chamber with its periphery closing the mouth thereof, said reaction-wheel having a central fluid-receiving chamber, and equidistant radiating jet-passages opening into the expanding-chamber at the periphery of the wheel, with means for introducing elastic fluid into the wheel, comprising an injector-head, connected with the fluid-supply, and with the vacuum-chamber or condenser.

7. In a turbine-engine, the combination of an expanding-chamber, a reaction-wheel located axially of and discharging into said chamber, and an injector-head for supplying fluid to said reaction-wheel; with means connected with and operated by said injector-head for exhausting pressure from the sides of the reaction-wheel, exterior to the expanding chamber.

8. In a turbine-engine, the combination of a casing having an annular expanding-chamber, with an internal open mouth, a reaction-wheel mounted to rotate axially of said expansion-chamber, with its periphery closing

the mouth thereof, and provided with a central receiving-chamber and equidistant radially-disposed fluid-passages discharging tangentially into said expansion-chamber, 5 and a jet-head adapted to discharge fluid axially into said wheel.

9. In a turbine-engine, the combination of a casing having an annular expanding-chamber provided with an internal annular open 10 mouth, a reaction-wheel located axially of said chamber with its periphery closing the mouth thereof and adapted to discharge fluid tangentially into said chamber; with an injector-head for directing fluid into said 15 reaction-wheel, and means to relieve pressure or skin friction on the wheel, substantially as described.

10. In a turbine-engine, the combination of a plurality of expanding-chambers, a reaction-wheel for each chamber located axially thereof and discharging thereinto, and 20 jet-heads directing fluid axially into each reaction-wheel.

11. In a turbine-engine, the combination of a plurality of annular expanding-chambers, each having an internal open mouth, a reaction-wheel mounted to rotate axially of 25 each expansion-chamber with its periphery closing the mouth thereof, and provided with a central receiving-chamber and equidistant 30 radially-disposed fluid-passages discharging tangentially into such expansion-chamber, jet-heads for directing fluid axially into the several wheels; and means for conducting 35 partly-expanded fluid from the first expansion-chamber to the next-wheel jet-head, substantially as set forth.

12. In a turbine-engine, the combination of a plurality of annular expanding-chambers, each having an internal annular open 40 mouth, a cylindrical reaction-wheel located axially of each chamber with its periphery closing the mouth thereof and adapted to discharge fluid thereinto; with an injector-head for directing fluid successively to said 45 reaction-wheels, and suction-pipes connected

with said head and with the wheel-chambers to relieve pressure or skin friction on the wheels, substantially as described.

13. In a turbine-engine, the combination 50 of the casing having an annular expansion-chamber, and a central wheel-chamber, a reaction-wheel mounted axially of said chamber and provided with internal radially-disposed equidistant jet-passages adapted to 55 discharge fluid tangentially into said expansion-chamber; with an injector-head connected with the fluid-supply adapted to direct fluid into said wheel; a suction-pipe connected with said head, and pipes connecting 60 said suction-pipe with the wheel-chamber exterior to the wheel, for the purpose and substantially as described.

14. In a turbine-engine, the combination 65 of a plurality of annular expansion-chambers, a reaction-wheel mounted axially in each chamber and provided with internal radially-disposed equidistant jet-passages adapted to 70 discharge fluid tangentially into said expansion-chamber; with an injector-head connected with the fluid-supply and adapted to direct fluid into the first wheel, means for directing partly-expanded fluid from the first expansion-chamber into the next wheel, a suction-pipe connected with 75 said head and pipes connecting said suction-pipe with the wheel-chambers exterior to the wheel, for the purpose and substantially as described.

15. In a turbine-engine, the combination 80 of a reaction-wheel, a fluid-passage leading to said wheel, and connections whereby the inflowing fluid creates a partial vacuum around the inactive parts of the wheel.

In testimony that I claim the foregoing as 85 my own I affix my signature in presence of two witnesses.

HENRY A. DUC, JR.

In presence of—

AETHUR E. DOWELL,
LILLIAN E. WITTHAM.
